RALPH HAYS DANNER, OF LOS ANGELES, CALIFORNIA.

ROTARY PUMP.

1,030,166.

Specification of Letters Patent. Patented June 18, 1912.

Application filed September 12, 1911. Serial No. 648,845.

To all whom it may concern:

Be it known that I, RALPH H. DANNER, a citizen of the United States, and a resident of Los Angeles, in the county of Los Angeles and State of California, have invented a new and Improved Rotary Pump, of which the following is a full, clear, and exact description.

The object of the invention is to provide a new and improved rotary pump, more especially designed for use in bored or driven wells, and arranged to prevent the bearings of the pump shaft from being cut by sand or other extraneous matter.

For the purpose mentioned, use is made of a fixed bearing post extending centrally in the well casing, pumping elements having hubs journaled on the said post, and a tubular driving shaft connected with the hubs of the pumping elements and through which extends loosely the fixed bearing post.

A practical embodiment of the invention is represented in the accompanying drawings forming a part of this specification, in which similar characters of reference indicate corresponding parts in all the views.

Figure 1 is a sectional side elevation of the rotary pump with the parts shown in elevation; Fig. 2 is an enlarged sectional side elevation of the upper portion of the rotary pump; Fig. 3 is a like view of the lower portion of the pump; and Fig. 4 is a sectional plan view of the same on the line 4-4 of Fig. 3.

The well casing A is preferably made in tubular sections A¹, A², A³ and A⁴, of which the adjacent ends of the sections A¹ and A² are connected with each other by screwing into a collar B, and the adjacent ends of the sections A² and A³ screw into a similar collar B', while the section A⁴ is bolted or otherwise fastened to the top of the uppermost section A³ and the top section A⁴ is provided with an outlet A⁵ for the discharge of the water. On the upper end of the top section A⁴ is secured a bracket C, and a bracket D is secured on the lower end of the lowermost section A' of the well casing A to form an inlet for the water. The bracket D is preferably provided with a central portion D' from which radiate arms D² connected with a ring D³ provided with an exterior screw thread screwing into a collar E screwing on the lower end of the lowermost casing section A'.

Within the casing A is arranged a series

of pumping elements F, F' and F², preferably formed of propellers, and having their hubs F³ mounted to turn on a bearing post G, fixed at its ends in the top and bottom brackets C and D, and the said hubs F³ are connected with tubular sections H, H' and H² forming the driving shaft for the pumping elements F, F' and F², the upper portion of the upper section H² being provided with a pulley I connected by a belt I' with other machinery for imparting a rotary motion to the driving shaft and the pumping elements F, F' and F² attached to the said driving shaft.

It will be noticed that the hubs F³ of the pumping elements are mounted to rotate on the fixed bearing post G while the latter extends loosely through the sections H, H' and H² of the driving shaft and does not contact with the same.

The lower end of the hub F³ of the bottom pumping element F is mounted on a step J resting on the top of the central portion D' of the bracket D, the said step J being preferably in the form of washers through which extends the fixed bearing post G. The upper section H² of the tubular driving shaft is journaled in stuffing boxes or bearings K and K', of which the stuffing box or bearing K is attached to the top of the well casing section A⁴, while the bearing K' is attached to the top of the bracket C. A ball bearing L is arranged on the upper portion of the casing section H² and the bracket C so as to aid the step J in supporting the tubular driving shaft and the pumping elements F, F' and F² attached thereto. Guiding elements N are arranged immediately below the pumping elements F' and F², and the said elements N are screwed in the collars B and B' between the ends of the corresponding casing sections A¹, A² and A², A³, so that the said elements N are securely held in place.

By the arrangement described the tubular driving shaft formed of the sections H, H', H² attached to the hubs F³ of the pumping elements F, F' and F² can be readily filled with oil or other lubricant from the top of the upper section H² so as to keep the hubs F³ of the pumping elements F, F' and F² properly lubricated on the fixed bearing post G. It will further be noticed that by the arrangement described the sand, grit and other extraneous matter cannot pass to the bearing surfaces between the hubs F³ of the

pumping elements and the bearing post G, and consequently the said bearings are not liable to be cut up by the sand, grit or other extraneous matter, and long life of the rotary pump is insured. It is further understood that the pumping elements are spaced suitable distances apart, and as many pumping elements are employed as required according to the depth of the well, each pumping element pumping the water upward in spiral form in the casing A to the next guiding element N, at which the next pumping element takes hold of the water and forces it upward in the casing A, the same as the first pumping element, and this operation is repeated until the water finally reaches the outlet spout A⁵ in the top section A⁴ of the well casing.

By reference to the drawings, it will be noted that each propeller is provided with two spirally arranged diametrically opposite propeller blades whereby the water is thrown straight upward instead of toward the center, thus insuring an easier lifting of the water.

Having thus described my invention, I claim as new and desire to secure by Letters Patent:

1. A rotary pump of the class described, provided with a central bearing post, a series of pumping elements having tubular portions circumjacent said post, tubular members also circumjacent said post and connecting said pumping elements in spaced relation, said tubular members and said tubular portions of said pumping elements being spaced from the said post and forming a tubular driving shaft, means for driving said shaft, and means for closing the lower end of said driving shaft to prevent the entrance of any of the fluid being pumped.

2. A rotary pump of the class described, comprising a well casing, a bearing post extending centrally in the said well casing and fixed at its ends, a series of pumping elements mounted circumjacent the said bearing post within the said well casing, tubular members also circumjacent the post and connecting the pumping elements and forming therewith a tubular driving shaft, the said bearing post extending loosely through the said driving shaft sections and means to close the lower end of said driving shaft to prevent the entrance of any of the fluid being pumped.

3. A rotary pump of the class described

provided with a well casing provided with brackets at top and bottom, a bearing post extending centrally in the said well casing and fixed at its ends in the said brackets, a series of pumping elements having hubs mounted to turn on the said bearing post, a tubular driving shaft made in sections secured to the said hubs, the said bearing post extending loosely through the said driving shaft sections, and driving means at the upper end of the driving shaft for driving the latter and with it the pump elements.

4. A rotary pump of the class described provided with a well casing provided with brackets at top and bottom, a bearing post extending centrally in the said well casing and fixed at its ends in the said brackets, a series of pumping elements having hubs mounted to turn on the said bearing post, a tubular driving shaft made in sections secured to the said hubs, the said bearing post extending loosely through the said driving shaft sections, a bearing on the bottom bracket for the lower end of the hub of the lowermost pumping element adapted to close the latter in fluid tight relation, and a bearing at the top bracket for the uppermost driving shaft section to turn in, and driving means on the upper end of the driving shaft.

5. A rotary pump of the class described, comprising a well casing, a bracket secured on the lower end of the said well casing and projecting below the same, the said bracket having water inlet openings and a central portion, a bracket at the upper end of the said well casing, a bearing post fixed in the said top and bottom brackets and extending centrally through the casing, a series of pumping elements having hubs journaled on the said post, a sectional driving shaft secured to the hubs of the pumping elements and through which extends loosely the said fixed bearing post, said central portion of said lower bracket forming a bearing step to engage the hub of the lowermost pumping element in fluid tight relation and thus close the lower end of the shaft, and upper bearings on the said bracket for the upper end of the said driving shaft.

In testimony whereof I have signed my name to this specification in the presence of two subscribing witnesses.

RALPH HAYS DANNER.
